UNITED STATES PATENT OFFICE.

WILLIAM H. BORDEN, OF WINCHESTER, MASSACHUSETTS, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,145,055.

Specification of Letters Patent.

Patented July 6, 1915.

Application filed June 28, 1909. Serial No. 504,759.

To all whom it may concern:

Be it known that I, WILLIAM H. BORDEN, a citizen of the United States, residing at Winchester, in the county of Middlesex and 5 State of Massachusetts, have invented certain Improvements in Machines for Use in the Manufacture of Boots and Shoes, of which the following description, in connection with the accompanying drawings, is a specification, like reference characters on the drawings 10 indicating like parts in the several figures.

This invention relates to machines for operating upon the soles of boots and shoes, 15 and particularly to a machine for trimming a sole while it is being attached.

In the manufacture of the better grades of shoes, such, for example, as Goodyear welt shoes, it is customary to employ outsoles 20 which have not been brought to approximately their final shape before being laid upon the shoe. The reasons for this practice will be apparent when the nature of the 25 earlier steps in the manufacture of a shoe of this type is considered. In order that the operations following the sole laying operation may be performed conveniently it is practically essential, in manufacturing shoes in which soles of the type above referred to are employed, to perform what are 30 usually termed "rough rounding operations". There are usually two of these rough rounding operations, one for bringing the forepart of the sole into approximately its final outline, and the other for 35 bringing the heel seat end of the sole into approximately its final outline. According to the usual practice the forepart of the sole is rough rounded and attached to the 40 welt before the heel seat end of the sole is attached, the attachment of the heel seat end of the sole to the insole, or to the insole and upper, being usually effected by means of 45 metallic fastenings. According to the present practice the rough rounding of this end of the sole may take place either before or 50 after the attaching operation. Probably the most usual practice is to attach the heel seat end of the sole and then to rough round it with a rotary cutter. Another practice is to round the heel seat end of the sole by a cutter shaped to fit against and to be guided by the counter of the shoe in advance of the

attaching operation. It will be noted, however, that by either practice the heel seat 55 rough rounding operation is a separate step in the manufacture of the shoe and that, furthermore, when the rotary cutter is employed the material trimmed off is of no further use. At a later stage in the manufacture of the shoe the sole edge trimming operation, which brings the sole to its final 60 outline, takes place.

The present invention aims to do away with the separate heel seat rough rounding 65 step in the manufacture of shoes and also to effect the cutting in such a manner that the material trimmed off may be utilized for other purposes. With this end in view the invention aims to provide a machine in which 70 the rough rounding operation may be performed simultaneously with, or as a part of, some other operation upon the shoe and preferably with some other operation upon the sole. 75

The invention aims further so to combine sole trimming means with other means for operating upon the shoe that the usual functions of the other means will not be interfered with by the trimming operation and 80 that additional work will not be imposed upon said means in the performance of said functions.

In the preferred embodiment of the invention, the heel seat rough rounding operation will be performed during the attachment of the heel seat. Preferably the cutting of the sole will be effected in a step by 85 step manner so that it may bear a proper relation to the row of successively inserted 90 fastenings with which the heel seat is usually attached. Furthermore the cutting will preferably bear a determined relation to the feeding of the work and will preferably be along the line of feed. 95

In one important aspect therefore the invention may be said to comprise the combination with means for successively inserting fastenings into work fed past said means of means for trimming the work in a step by 100 step manner operating along the line of the work feed. Preferably the trimming operation will take place after the work has been fed, provision being preferably made for clamping the work to hold it against the 105 action of the trimming means which will

preferably move along the work. Preferably the direction of movement of the trimming means as it moves to trim the work will be opposed to that in which the work is fed, this arrangement permitting the more convenient employment of work feeding means, particularly the ordinary type of work feeding means in which the awl which forms the fastening receiving opening in the work is employed to feed the work. This arrangement also insures continuity of the trimming, that is, continuity of the successive cuts, and permits the trimming to conform more closely to the desired final outline.

15 In another aspect, therefore, the invention may be said to comprise means for successively inserting fastenings into work fed past said means, of means for trimming the work after each feeding step, preferably operating along the work in a direction opposed to that in which the work is fed.

When looked upon as an improvement in trimming mechanism the invention, in one aspect, may be said to comprise means for feeding the work and means for trimming the work movable along the line of the work feed. Or, when combined, for example, with means for clamping the work at the end of a feeding step, the invention, in another aspect, may be said to comprise, in a trimming machine in which provision is made for holding the work stationary after a feeding step, means for effecting a step-wise trimming of the work operating while the work is held stationary.

In the preferred embodiment of the invention the trimming means has an inoperative movement during the operative movement of the feeding means or during the feeding operation, and an operative movement during the inoperative movement of the feeding means or after the work has been fed, and this timing and the arrangement by which it is brought about constitute important features of the invention. It will be noted that when feeding means is provided, this timing permits the convenient actuation of the trimming means by mechanism constituting a part of, or associated with, that which actuates the feeding means.

Preferably the inoperative movement of the trimming means is greater and faster than the operative movement of the feeding means whereby the trimming means may be withdrawn from its previous cut to permit free turning of the work during the feeding operation and to prevent damage to the trimming means by such turning. This arrangement contributes much to the practicability of the combination of trimming means with a machine of the type herein illustrated and constitutes an important feature of the invention.

65 To insure proper gaging of the trimming,

the gaging means is preferably movable with the trimming means and in the preferred embodiment of the invention in which the trimming takes place after a work feeding operation the gage is preferably movable with the work as the work is fed.

In some classes of work it is desirable not only that the edge of the sole be rough rounded, but also that the trimming or randing of the upper edge of the sole be started. Provision has therefore been made in the present invention for effecting a randing of the sole as the edge of the sole is trimmed, and an important feature of the invention is the novel means for this purpose. It will be apparent that the provision of this means in a machine having some or all of the different features hereinabove pointed out presents many novel and useful combinations. To these various combinations attention will not be directed here in detail, but it is my intention to make them the subject-matter of several of the claims.

It will be noted that in the preferred embodiment of the invention advantage has been taken of the movement and position of the gaging means, hereinabove referred to, to provide simple and effective means for supporting and actuating the rand trimming means and to the novel combinations involved in this arrangement attention will be especially directed in the appended claims.

Other important features of the invention and new and useful combinations of elements will be set forth in the following description and claims, and the purpose and nature of the invention will be more fully understood when the description and claims are read in connection with the accompanying drawings illustrating a preferred embodiment of the invention.

In the accompanying drawings.—Figure 1 is a front elevation of the upper part of a machine for inserting fastenings having embodied therein this invention, the usual fastening container and raceway being omitted from this view; Fig. 2 is a perspective view of the trimming mechanism; Fig. 3 is a detail view showing in side elevation the means for operating the trimming mechanism; Fig. 4 is a perspective view of the trimming mechanism looking from below, showing also the guard plate through which the fastenings are inserted and through which the awl operates; Fig. 5 is a detail plan view showing the cutting knife set to cut in from the outer edge of the sole at the beginning of the operations upon the sole; Fig. 6 is a detail plan view showing the cutting mechanism in its normal operative relation to the sole to be trimmed and showing in dotted lines the position of

the trimming knife before the work has been fed into position to receive the first fastening; Fig. 7 is a detail perspective showing the nature of the trimming operation and its relation to the lasted upper; and Fig. 8 is a plan view of a nailed and trimmed heel seat after the shoe has been operated upon by the machine of this invention. Fig. 9 is a side elevation of a portion of the machine, illustrating especially the mechanism for clamping and releasing the work.

The fastening inserting machine with which the invention is herein shown as associated or in which it is embodied is of the type illustrated in the patent to Louis Goddu, No. 490,624, Jan. 24, 1893, and is known to the trade as the "loose nailing machine". For a detailed description of the parts of this machine herein illustrated but not specifically described reference may be had to the said patent, and so far as the parts of said machine are herein described such description will be made by reference 25 to parts of the drawing lettered as in the said patent.

The machine has a head A mounted upon a column or standard A' in which are bearings for the main driving shaft C². The various cams through which operative movements are imparted to the different mechanisms in proper timed relation to each other are carried by the main shaft C². At the front of the machine is a swinging head or frame B in which reciprocate in a vertical plane the driver bar a carrying the driver a⁵ and the awl bar f⁸ carrying the awl f⁹. The head is swung when the awl is in the work to feed the work and the mechanism for swinging the head comprises a rock-shaft D² mounted in bearings D³ and B³, said rock-shaft being rocked by an arm D' clamped upon it and carrying at its outer end a cam roll traveling in a cam groove in the cam disk D upon the main shaft C². At its forward end the rock-shaft carries an arm D⁴ connected to the head B in the manner described in said patent whereby said head is swung to feed the work. All of the parts thus far described, with the exception of the arm D', may be substantially those disclosed in said patent and such as are in common use.

The trimming mechanism, which may conveniently be formed as an attachment to be put upon the commercial loose nailing machine or other fastening inserting machine for trimming heel seats while they are being nailed, comprises, in a preferred embodiment, a bracket 2 bolted to the column A' or to a clamp member 3 of a clamp surrounding said column, said bracket having lateral curved ways 4 and 6 for a carriage 8 carrying the trimming knives and the gage or guide. The carriage is reciprocated to

cause the trimming knife or knives to effect the trimming operation by means of suitable connections with the driving shaft of the machine, the connections herein shown comprising an extension 10 of the rock arm D' 70 below the rock-shaft D², the arm 10 being connected by the link 12 to a lever arm 14 pivoted at 16 upon an ear 18 formed upon the bracket 2.

At its end remote from the pivot 16 the 75 lever 14 is connected by a link 22 to the carriage 8. The ways 4 and 6 are curved in concentric arcs in order that the trimming knife in its trimming movement may move in a curved path, thereby approximating the 80 desired contour of the work to be trimmed. Preferably two trimming knives are provided, one for trimming the edge of the sole and the other for randing its upper face, although the latter knife may be dispensed with on some kinds of work. The edge trimming knife is herein shown as having an upstanding sharpened blade portion 24 and a rearwardly extending stem portion 26, preferably dove-tailed in shape, 85 and adjustably confined in a dove-tailed groove in a holder 28 by the clamping plate 30.

The normal position of the edge trimming knife is illustrated in Figs. 1, 2, 4 and 6. In 90 this position the knife is adapted to trim the work in a line substantially parallel with the line of feed. When the knife is to operate upon a blocked sole, for example, which projects considerably in the region 100 of the shank whereby it is necessary to cut in from the side in order to bring the knife into the desired relation to the upper for the succeeding trimming steps, it is desirable that provision be made for moving the 105 knife automatically into the desired relation to the upper, and a feature of the invention is the provision of means for effecting such a movement of the knife. To this end the knife holder is preferably so constructed 110 and arranged that it may be adjusted to cause the knife to make a first cut at an angle to the line which it will follow in the succeeding trimming steps. To permit such adjustment the knife holder is preferably 115 carried upon a segment 32 pivoted at 34 upon the carriage 8, said segment being provided with teeth 36 which mesh with teeth 38 upon a segment lever 40 pivoted at 42 on the carriage 8.

The lever 40 has a rearwardly extending arm 44 arranged to engage an adjustable stop 46 upon the bracket 2 when the carriage 8 is moved from right to left, Figs. 5 and 6, during the work feeding movement of the awl, and thereby to cause the segment 32 to be turned in a counter-clockwise direction about its pivot. This turning movement of the segment 32 serves to restore the knife 24 to its normal position after it has 120

been turned into the position shown in Fig. 5, and as it is thus restored to its normal position to cause it to cut in from the edge of the work in advance of its first trimming movement.

5 A spring 48 normally tensioned and connected at one end to a stud 50 on the arm 44 and at its other end to a stud 52 on the carriage 8 tends to draw the arm 44 into contact 10 with the stop 46. The normal position of the knife 24 is determined by an adjustable stop 54 carried by a lug 56 upon the carriage 8.

15 To keep the segment 32 from turning during the trimming operation means is preferably provided for locking it in normal position. The illustrated means comprises a spring-pressed bolt 58 arranged to enter a notch 60 in the side of the segment 32 when 20 said segment is in normal position, said bolt having on its under side a shoulder 62 (see Fig. 4) arranged to be engaged by a push pin 64 provided with a thumb piece 66 whereby the operator may push the bolt 58 25 out of engagement with the notch 60, thus permitting the segment 32 to be turned into the position shown in Fig. 5 by the action of the spring 48 upon the arm 44.

30 Before the trimming operation begins, that is when the carriage moves from right to left in Fig. 5 or Fig. 6, as the work is fed to bring the first awl hole 68 beneath the driver 63, the arm 44 will engage the stop 46 and the knife 24 and its holder 28 will be 35 turned about the pivot 34, thus causing the knife to cut into the edge of the work and come into its normal position in advance of the return movement of the carriage 8 when the knife will make a cut substantially parallel with the line of feed of the work.

40 The actuating connections, including the lever 14, are preferably so proportioned that the inoperative movement of the trimming knife 24 is greater than the work feeding 45 movement of the awl in order that the knife may be drawn back from the closed end of its cut to permit the work to be turned freely without danger of breaking the knife. To permit adjustment of the movement of the 50 carriage 8 to accommodate it to different lengths of work feed, the lever 14 is preferably provided with a series of holes 70 into which fits the post carrying the ears 72.

55 To permit the initial adjustment of the carriage 8 and knife 24 the link 12 is preferably made in two parts comprising a clamping sleeve 121 pivotally connected to the arm 10 and a member 122 having a stem extending into the sleeve 121, said member 60 122 being pivoted between the ears 72.

65 The gage which determines the location of the row of nails with respect to the edge of the work and also the amount of material to be trimmed from the edge is shown at 74, and as herein illustrated is shaped to en-

gage the counter in the region of the rand crease. The gage 74 is adjustably connected to the gage carrier 76 by a set screw 78 passing through a horizontal slot in the carrier 76 whereby said gage may be both angularly and bodily adjusted on said carrier. The carrier 76 is pivotally mounted upon the carriage 8 between upstanding ears 80 and is normally held in its uppermost position by a spring 82. The uppermost position of the gage 74 is yieldingly determined by a second spring 84 bearing against the under side of its rear end whereby upward movement of the gage with the work beyond its normal position is permitted. Preferably means is 75 provided for varying the tension of the spring 84 in order to vary the normal position of the gage 74. The part of the gage which contacts with the upper is preferably made of brass as it has been found that this 80 does not rub the upper as much as some other metals.

85 To prevent the trimming from riding up over the upper end of the knife 24 a groove 86 is preferably provided in the under side 90 of the guard plate 88 in which said upper end of the knife travels. For convenience in adjusting the knife this groove is preferably formed by making the guard plate in two parts, 881 and 882, the part 881 being 95 preferably stationary and the part 882 having a stem 90 provided with slots through which pass set screws 92 whereby said part may be adjusted to adapt it to different positions of the knife 24.

100 With the mechanism thus far described the edge of the sole may be trimmed. It is, however, frequently desirable to rand the upper face of the sole somewhat to permit the rotary rand trimmer used in the finishing operation more readily to enter the rand crease.

105 In the illustrated construction novel means for effecting this randing operation is provided. Advantage is taken of the fact that the gage 74 travels with the work during the work feeding operation to mount the rand trimming cutter upon said gage so that as the gage returns to its initial position it will effect a randing of the work. Preferably this rand trimming cutter will operate in advance of the edge trimming cutter, and in the illustrated construction the rand trimming cutter is shaped to cut a groove 110

115 or channel in the upper face of the sole in such position that the edge trimming cutter will travel approximately through the middle of said groove or channel, thereby leaving a beveled or randed edge upon the trimmed part of the sole. The rand trimming knife or cutter is shown at 94 and is 120 mounted upon the upper side of the gage 74, said gage being cut away somewhat beneath the arched cutter blade 94 to provide a passage for trimmings. The stem 96 of the cutter 125 94 is provided with slots through which 130

135

the attaching screws 98 pass, whereby adjustment of the cutter transversely to the line of feed of the work is permitted. The cutting edge of the cutter 94 is upon the 5 right-hand side as the cutter is viewed in Figs. 5 and 6.

The operation of the machine may be briefly recapitulated as follows: The shoe, upon which the sole to be nailed and rough 10 rounded has been laid, is placed upon the work support, which may be the jack 100 shown in Fig. 1, and the machine is then started. If the sole is a blocked sole, for example, and the shank of the shoe is considerably narrower than the shank of the 15 sole, the operator, before he starts the machine, will press in the push pin 64 by means of the thumb piece 66, thereby moving the bolt 58 out of the notch 60, thus permitting 20 the segment 32 to be turned into the position shown in Fig. 5 by the action of the spring 48 upon the arm 44 of the segment lever 40. The knife 24 will thus be moved into a position such that when the carriage moves toward 25 the left in Figs. 5 and 6, as the awl moves to feed the work, the knife will cut in from the edge of the sole, as shown in Fig. 6, and thus come into position to effect the proper trimming cut upon the movement 30 of the carriage toward the right in these figures, as the awl returns to initial position. As hereinabove pointed out, the movement of the knife into its normal trimming position is effected by the engagement of the 35 arm 44 of the segment lever 40 with the stop 46 upon the bracket.

In Fig. 6 the work is shown after the first awl hole 68 has been made, and the work has been fed into position to receive the first nail 40 or other fastening. The cut illustrated in this figure has been made by two movements of the knife 24, one movement being about the pivot 34 by which the knife has cut in from the edge and come into its normal cutting position, and the second movement being in an arc having a center common with the arc of the path to travel of the carriage 8, the first movement, as above indicated, taking place when the carriage moves toward 45 the left in Figs. 5 and 6 as the awl feeds the work, and the second movement taking place when the carriage moves toward the right as the awl returns to its initial position. After these two movements are completed the fastening inserting operation 50 takes place. It will thus be seen that the centers of the two movements of the knife 24 are upon opposite sides of the line of cut. When the knife has come into the position 55 illustrated in Fig. 8 the bolt 58 enters the notch 60 and the knife is locked in this position, so that succeeding cuts lie in arcs having a center common with the center of the arc of the path of travel of the carriage 8. The shoe is pressed against the gage 74,

the upper bearing against the side of the gage and the sole projecting over the upper face. When the jack 100 is raised under the action of the usual spring provided in the machine disclosed in the patent above 70 referred to to cause the sole to be clamped against the guard plate 88, the gage 74 will travel up with the shoe and sole under the action of the spring 82 and also under the action of the shoe, since the gage is so 75 shaped that it tends to enter somewhat the rand crease between the sole and the upper. The rand trimming cutter 94 will thus be brought into operative relation to what will be the upper face of the sole in the finished 80 shoe, and as the gage 74 moves with the carriage 8 the cutter 94 will cut a groove in this face of the sole upon the return movement of the carriage after the work has been fed. This groove will be split by the knife 85 24 which follows the cutter 94 so that part of the groove will be left upon the trimmed sole and the other part will be upon the trimming which is removed. After the 90 nailing has proceeded around to a point opposite the starting point upon the other side of the sole, the operator can remove the shoe and complete the severing of the trimming by dragging the sole over the stationary knife after the machine has been stopped, 95 thus bringing the last cut out to the surface, if the sole is not of such shape that the movement of the cutter itself has effected the complete severing of the trimming.

The nailed heel seat and the trimming removed from a blocked sole are illustrated in Fig. 8. It will be understood, however, that the invention is not limited to nailing and trimming heel seats. It will be understood further that the invention is not limited to 105 the combination of trimming mechanism with nailing mechanism, but that it embraces both the novelty in the various combinations, herein disclosed, of the elements of the trimming mechanism with the elements of the nailing or fastening inserting mechanism, and also the various features of novelty of the trimming mechanism *per se*.

It will be noted that the cut made by the knife 24 is a paring cut as distinguished 115 from a chopping cut or a drag cut, and that the nature of this cut contributes much to the practicability of the employment of mechanism of this type in conjunction with fastening inserting mechanism. It will be 120 noted further that the cut made by the knife or cutter 94 is produced by a movement of said cutter similar to the movement of the knife 24.

An important feature of the invention and 125 one which has also contributed much to the practicability of combining trimming mechanism with fastening inserting mechanism is the arrangement by which the trimming cut is made after the shoe has been fed, 130

whereby no additional work is put upon the machine during the performance of its ordinary functions.

Although the invention has been shown 5 herein as combined with a loose nailing machine and also as combined with a loose nailing machine of particular type, it will be understood that it is not intended to restrict the invention to use either with loose nailing 10 machines or with loose nailing machines of the type herein illustrated as it will be evident that the invention may readily be combined with other machines.

In some of the following claims reference 15 will be made to clamping the work after the work feeding operation or to holding the work stationary for the trimming operation, and it will be understood that the work support employed with this machine may be 20 actuated to clamp and release the work by any suitable mechanism, such for example, as that ordinarily employed with the commercial loose nailing machine. A common type of work support clamping and releasing 25 mechanism and one suitable for the purposes of the machine of this application is illustrated in United States patent to Louis Goddu, No. 265,227, Sept. 26, 1882, reference being had especially to Figs. 1 and 2 of said 30 patent. In Fig. 9 of the drawings this work support clamping and releasing mechanism is illustrated sufficiently for the purposes of this application. A pawl carrying slide 130 is reciprocated by suitable connections with 35 a cam groove formed in the front face of the brake disk 132, the illustrated connections comprising a rod 134 pivotally connected to one arm of a lever 136 fulcrumed at 138 on the machine frame, another arm 40 of this lever carrying the cam roll 140 which enters the cam groove in the brake disk 132. The pawl 142 is adapted to engage one of the ratchet teeth 144 upon a second slide 146 which has operative connection, through a 45 lever in the base of the machine in the usual manner, with a jack supporting post 148. During the downward part of the reciprocatory movement of the slide 130, the pawl 142 is moved out of engagement with the 50 ratchet teeth upon the slide 146 by means of a pawl tripping plate 150. A spring 151, acting upon the jack post 148 in the usual manner, causes the jack to press the work against the guard plate 88 so that when the 55 pawl again engages one of the ratchet teeth 144 on the slide 146 at a predetermined point in its path of movement, the amount of releasing movement imparted to the jack will be adjusted to the thickness of the work and 60 the work will be depressed each time the same distance from the guard plate.

It will be understood that the principal purpose of releasing the work after the clamping action is to permit the work to be 65 fed freely. It will be understood further

that the invention is not limited to clamping the work to hold it stationary, but that other means may be employed to hold the work stationary for the action of the trimming mechanism and that such means need 70 not necessarily be independent of the feeding mechanism.

While the present invention, in so far as the tools for cutting the sole are concerned, is intended primarily for the operation of 75 rough rounding and randing the heel seats of boot and shoe soles, it will be apparent to those skilled in the art that many of the novel combinations of elements, which include the cutting tools, are adapted to a sole 80 trimming operation. That portion of the invention relating to the cutting of the sole has, therefore, been purposely described by the use of broad terms, but the true scope of the invention will be found in the appended claims wherein the terms "rough rounding" and "trimming" are properly applied to the cutting tools in accordance with whether the whole combination claimed 85 is novel for a heel seat rough rounding operation or the more comprehensive sole trimming operation.

Having described my invention, what I claim as new and desire to secure by Letters Patent of the United States is:

1. The combination with means for successively inserting fastenings in a shoe sole along a line substantially parallel to the contour line of the finished sole, of means for trimming said sole substantially to said contour arranged to operate only between the successive fastening inserting operations.

2. The combination with means for successively inserting fastenings in a shoe sole along a line substantially parallel to the contour line of the finished sole, of means for trimming said sole substantially to said contour arranged to operate between the successive fastening inserting operations along a path having a curvature approximating that 100 of said contour.

3. The combination with means for successively inserting fastenings in a shoe sole along a line substantially parallel to the contour line of the finished sole, and means for feeding the work between the successive fastening inserting operations, of means associated with said work feeding means and operating upon the return movement thereof for trimming said sole substantially to 110 said contour.

4. The combination with means for successively inserting fastenings in a shoe sole, of means for trimming the edge of said sole arranged to operate only between the successive fastening inserting operations and along a curved path the center of which lies within said sole edge.

5. The combination with means for successively inserting fastenings in a shoe sole, and 130

gaging means arranged to engage the adjacent portion of the upper to determine a line of inserted fastenings corresponding to the upper contour, of means for trimming the edge of said sole arranged to operate between the successive inserting operations and to move about a center which is located upon that side of the point of operation of the inserting mechanism remote from said gaging means.

6. The combination with means for successively inserting fastenings in a shoe sole, of means for effecting a step-by-step trimming of the shoe sole alternating in its operation with the operations of the inserting mechanism, said means having its operative movement along the sole edge in a curved path the center of which lies within said edge.

7. The combination with means for successively inserting fastenings in a shoe sole, and gaging means arranged to engage the adjacent portion of the upper to determine a line of inserted fastenings corresponding to the upper contour, of means movable along the sole edge for trimming said edge, said means being arranged to operate only between the successive fastening inserting operations and having its operative relation to said shoe determined by said gaging means.

8. A machine of the class described, having, in combination, a swinging head, an awl carried by said head, means for swinging the head while the awl is in the work to feed the work, and means operated by said last-named means for trimming the work upon the return swing of the head.

9. A machine of the class described, having, in combination, means for feeding the work, means for clamping the work at the end of the work feeding operation, and means movable along the work after it has been clamped for trimming the work.

10. A machine of the class described, having, in combination, means for intermittently operating upon the work, means for feeding the work between successive operations of the operating means, means for releasing the work during the work feeding operation, means for clamping the work for the operation of said operating means and cutting means operating along the line of the work feed, while the work is clamped, for trimming the work.

11. A machine of the class described, having, in combination, means for feeding the work, means for clamping the work at the end of the work feeding operation, and a knife movable in the direction of the work feed during the work feeding operation and movable in a direction opposed to that of the work feed when the work is clamped for trimming the work.

12. A machine of the class described, having, in combination, edge trimming means

and work feeding means, the cut of said edge trimming means being along the line of the work feed and means for withdrawing said trimming means from its cut while the work is being fed.

13. A machine of the class described, having, in combination, edge trimming means and work feeding means, the cut of said edge trimming means being along the line of the work feed in a direction opposed to said feed, and means for operating the edge trimming means constructed to withdraw it from its cut while the work is being fed.

14. A machine of the class described, having, in combination, reciprocating means for feeding the work and means traveling along the line of the work feed for trimming the work, said two means being so operatively connected that said trimming means has inoperative movement during the operative movement of the work feeding means and operative movement during the inoperative movement of the work feeding means.

15. A machine of the class described, having, in combination, means for feeding the work and means for trimming the work having inoperative movement during the operative movement of the work feeding means and operative movement during the inoperative movement of the work feeding means, said inoperative movement of the trimming means being greater than the operative movement of the feeding means.

16. A machine of the class described, having, in combination, trimming means movable along the work and work feeding means, said trimming means having an inoperative movement in the direction of the operative movement of said feeding means, and an operative movement in a direction opposed to the direction of operative movement of the feeding means, said inoperative movement of the trimming means being greater and faster than the operative movement of the feeding means.

17. A machine of the class described, having, in combination, mechanism for successively inserting fastenings into work fed past said mechanism, means for feeding the work between the successive fastening inserting operations, and means for trimming the work operating after a work feeding operation and before the succeeding fastening inserting operation.

18. A machine of the class described, having, in combination, means for inserting fastenings, means for feeding the work, and means operated during the return of said work feeding means into normal position for trimming the edge of the work.

19. A machine of the class described, having, in combination, means for inserting fastenings, means for feeding the work, and means operating during the return of the

- work feeding means to normal position for trimming the edge of the work, said means having a greater movement in the work feeding direction than the work feeding means.
20. A machine of the class described, having, in combination, means for successively inserting fastenings into work fed past said means, and means for trimming the work movable along the line of the work feed, said trimming means comprising a vertically arranged knife supported at its lower end and a guard for the upper end of said knife.
- 15 21. The combination with means for successively inserting fastenings in a shoe sole, of work feeding means movable to and fro, and means for trimming the sole edge operating only upon the return movement of said work feeding means.
- 10 22. The combination with trimming means movable to and fro along the line of cut, of a gage movable with said trimming means, and automatic means for moving said trimming means and gage.
- 25 23. In a machine for operating on the heel seats of boot and shoe soles, a heel seat rough rounding knife, a cutter arranged to sever a portion of the stock from the flesh side of the heel seat, a gage comprising a portion arranged to bear against the counter of the shoe and determine the width of the cut produced by said cutter, and means for engaging and feeding the sole being operated upon.
- 30 24. In a machine of the class described, a gage arranged to engage the upper adjacent to the sole and movable with the work as the work is fed, a rand trimming cutter mounted upon the upper face of said gage and arched over a recess in said face whereby said cutter cuts a groove in the sole upon the movement of said gage in one direction and means for moving said gage.
- 35 25. A machine of the class described, having, in combination, mechanism for successively inserting fastenings into work fed past said mechanism, automatic means operating intermittently to feed the work between the successive fastening inserting operations, a gage for positioning the work, and trimming means carried by said gage.
- 40 26. A machine of the class described, having, in combination, mechanism for successively inserting fastenings into work fed past said mechanism, a gage for locating the work with respect to said mechanism and trimming means carried by said gage.
- 45 27. A machine of the class described, having, in combination, means for inserting fastenings, means for feeding the work, a gage for determining the location of the work movable with said work feeding means, and trimming means carried by said gage.
- 50 28. A machine of the class described, having, in combination means for inserting fastenings, means for feeding the work, a gage for determining the location of the work movable with said work feeding means and means carried by said gage for randing the edge of the work.
- 55 29. A machine of the class described, having, in combination, means for inserting fastenings, means for determining the line along which the fastenings are inserted, and means operating only between successive fastening inserting operations for trimming the edge of the work to bring it into parallelism with the line of fastenings.
- 60 30. The combination with means for successively inserting fastenings into work fed past said means and means for feeding the work step by step, of means for randing the edge of said work operating between the feeding steps.
- 65 31. The combination with means for successively inserting fastenings into the sole of a shoe fed past said means, of means for randing the upper edge of the sole operating between the successive fastening inserting operations.
- 70 32. The combination with means for successively inserting fastenings into the sole of a shoe fed past said means, of means for randing the upper edge of the sole having operative movement in a direction opposed to the feeding movement.
- 75 33. The combination with means for inserting fastenings at separated points in the sole of a shoe fed past said means, of means for cutting a continuous groove in the rand face of said sole extending parallel to the line of feed.
- 80 34. The combination with means for successively inserting fastenings into the sole of a shoe fed past said means, of means for cutting a groove in the upper face of said sole extending parallel to the row of inserted fastenings and means for trimming the sole operating between the sides of said groove.
- 85 35. The combination with means for successively inserting fastenings into the sole of a shoe fed past said means and means for feeding the shoe, of means for effecting a stepwise randing of the upper edge of said sole operating between the feeding steps.
- 90 36. The combination with means for feeding the shoe sole step by step, of means for trimming the sole and means for randing the sole operating simultaneously between the feeding steps.
- 95 37. The combination with means for feeding a shoe sole, of means for cutting a groove in the upper face of said sole parallel to the line of feed, and means for trimming the sole operating between the sides of said groove. Cor 4
125 Pg 7
- 100 38. A machine of the class described, having, in combination, edge trimming means arranged to travel along the line of the

- cut by which it severs the material to be trimmed from the edge and rand trimming means, also arranged to travel along the line of said cut, but in advance of the edge trimming means and in such relation thereto that the edge trimming means travels between the sides of the cut made by the rand trimming means, and means for effecting the movements of said trimming means.
- 5 39. A machine of the class described, having, in combination, means for feeding the work, means for grooving or channeling the work having an inoperative movement during the operative movement of the work feeding means and an operative movement 10 during the inoperative movement of the work feeding means, and means for cutting the work intermediate the sides of said groove or channel.
- 15 40. A machine of the class described, having, in combination, means for feeding the work, and grooving and cutting knives having inoperative movement during the operative movement of the work feeding means, and operative movement during the inoperative movement of the work feeding means, said cutting knife being arranged to cut the work along the groove formed by said grooving knife.
- 20 41. In a machine for operating upon soles which project at all points beyond the desired contour line, means for trimming a sole to the desired contour and means for causing said trimming means to effect automatically an initial cut from the edge of the sole to the contour line.
- 25 42. A machine of the class described, having, in combination, means for trimming step by step, to give it a contour substantially like that of the upper, a sole which projects beyond its desired contour at all points, and means for causing said trimming means to effect automatically an initial cut through said projecting portion of the sole 30 to the desired contour line.
- 35 43. In a machine for operating upon soles which project at all points beyond the desired contour line, means for trimming a sole to the desired contour, and means for causing said trimming means to effect automatically an initial cut of predetermined form from the edge of the sole to the contour line.
- 40 44. In a machine for operating upon soles which project at all points beyond the desired contour line, means for trimming a sole to the desired contour, and means for causing said trimming means to effect an initial cut along a predetermined line intersecting the edge of the sole and extending to the contour line.
- 45 45. The combination with means for successively inserting fastenings into the sole of a shoe fed past said means, of means for trimming the work in a stepwise manner op- 50 erating normally along the line of the work feed, said means having provision for adjustment to effect the first cut at an angle to the line of the work feed.
- 55 46. The combination with means for successively inserting fastenings into work fed past said means, of means for trimming the work in a stepwise manner operating normally along the line of the work feed, said means having provision for adjustment to cause it to effect two trimming cuts before the first fastening inserting operation, the first of said cuts being at an angle to the line of the work feed. 60
- 60 47. The combination with means for successively inserting fastenings into work fed past said means, of means for trimming the work in a stepwise manner operating normally between the feeding steps and along the line of the work feed, said means having provision for adjustment whereby it is caused to effect an initial cut during the work feeding operation at an angle to the line of the work feed. 65
- 65 48. A machine of the class described, having, in combination, means for feeding the work and means for trimming the work operating normally along the line of the work feed, said means having provision for adjustment whereby it operates automatically to effect an initial cut at an angle to the line of the work feed. 70
- 70 49. A machine of the class described, having, in combination, edge trimming means arranged to move along the line of cut and means for operating said trimming means constructed to cause said trimming means to make an initial cut at an angle to the path in which it travels in making its succeeding cuts. 75
- 75 50. A machine of the class described, having, in combination, means for feeding the work, means for trimming the work along the line of the work feed, and means for actuating said trimming means constructed to cause it to operate automatically to effect an initial cut at an angle to the line of the work feed. 80
- 80 51. In a machine of the class described, an edge trimming cutter, and means for operating the cutter constructed and arranged to cause the cutter to effect successive cuts in arcs the centers of which are upon opposite sides of the line of cut. 85
- 85 52. A machine of the class described, having, in combination, a reciprocating carriage, a cutter mounted upon said carriage and moved to cut with the movement of the carriage in one direction, and means under the control of the operator constructed and arranged to cause said cutter to cut, at the will of the operator, when the carriage moves in the other direction. 90
- 90 53. A machine of the class described, having, in combination, means for attaching the 95

heel seat end of a sole, means for trimming said sole to substantially the contour of the adjacent outline of the upper, and means for setting said trimming means so that the initial cut will be formed from the edge in 5 at an angle to the side of the adjacent portion of the upper.

54. A machine of the class described, having, in combination, a cutter arranged to cut 10 along the edge of a shoe sole to trim said edge, a gage arranged to engage the shoe and determine the projection of the trimmed sole, a carriage upon which said gage and cutter are mounted and intermittently operated means for moving said carriage to and fro.

55. A machine of the class described, having, in combination, mechanism for inserting fastenings, means for feeding the work 20 between the successive fastening inserting operations, a carriage movable along the line of the work feed, means operating between the fastening inserting operations for moving the carriage and an edge trimming cutter carried by the carriage.

56. A machine of the class described, having, in combination, mechanism for performing successive operations at separated points upon a sole, means for feeding the 30 work from point to point, a carriage movable along the line of the work feed between the operations of said mechanism and an edge trimming cutter and a shoe gage mounted upon said carriage.

57. A machine of the class described, having, in combination, mechanism for performing successive operations at separated points upon a shoe sole, means for feeding the work between said points, a carriage 40 movable to and fro along the line of the work feed, means for moving the carriage and an edge trimming cutter and a rand trimming cutter mounted upon said carriage and operating upon the return movement thereof.

58. A machine of the class described, having, in combination, mechanism for inserting fastenings, means for feeding the work, a carriage movable in arc-shaped ways along 50 the line of the work feed, means for moving the carriage in timed relation to the work feed, and an edge trimming cutter and a work gage mounted upon said carriage.

59. A machine of the class described, having, in combination, a driver and an awl, means for operating the awl to feed the work, a carriage mounted in arc-shaped ways to move along the line of the work feed, an edge trimming cutter and a work 60 gage mounted upon the carriage and means for moving the carriage associated with the means for moving the awl to feed the work.

60. A machine of the class described, having, in combination, fastening inserting 65 mechanism, a guard plate against which the

work is pressed and means for trimming the edge of the work comprising a cutter having a vertical cutting blade with a lateral cutting edge arranged to cut along the edge of the work, said guard plate having a recess into which the upper end of said blade extends.

61. A machine of the class described, having, in combination, mechanism for operating upon the sole of a shoe, a guard plate 70 against which the sole is pressed, and a trimming cutter arranged to move along said sole to trim its edge and comprising a vertical blade portion having a lateral cutting edge, said guard plate having a groove so in which the upper end of said blade travels.

62. A machine of the class described, having, in combination, mechanism for operating upon the sole of a shoe, a cutter having a lateral cutting edge arranged to move along 75 the sole for trimming its edge and adjustable toward and away from the point of operation of said mechanism, and a guide for the upper end of said cutter adjustable to adapt it to the different adjusted positions so of the cutter.

63. A machine for operating on the heel seats of boot and shoe soles, having in combination, means for feeding the sole being operated upon, a heel seat rough rounding 95 knife, a shoe gage, means for adjusting said gage transversely relative to said knife, and a rand knife mounted upon the gage and adjustable therewith.

64. A machine for operating on the heel seats of boot and shoe soles, having in combination, means for feeding the sole being operated upon, a heel seat rough rounding knife, a shoe gage, means for adjusting said gage transversely relative to said knife, a 100 rand knife mounted upon the gage, and means for adjusting said rand knife relative to said gage.

65. In a machine of the class described, edge trimming means, rand trimming means, 110 a gage for locating the work to be operated upon by said trimming means, all of said parts being arranged to reciprocate together in the line of feed, and means for effecting such movement.

66. In a machine of the class described, the combination with edge trimming means, comprising a knife adapted to effect in successive steps a continuous cut along the edge of a shoe sole to trim said edge, means for effecting a stepwise relative movement of the work to be trimmed and said knife, and means for randing the work simultaneously with the edge trimming operation.

67. A machine for operating on the heel seats of boot and shoe soles, having in combination, means for engaging and feeding the sole being operated upon, a heel seat rough rounding knife, and a rand knife, said latter knife being mounted for lateral 125 130

adjustment transverse of the direction of feed.

68. A machine for operating on the heel seats of boot and shoe soles, having in combination, a heel seat rough rounding knife, a separate randing knife, means for adjusting said randing knife relative to the rounding knife, and means for engaging and feeding the sole being operated upon to transfer 10 the point of operation of the knives progressively around the heel seat.
69. A machine for operating on the heel seats of boot and shoe soles, having in combination, a heel seat rough rounding knife, 15 a randing knife, a counter gage for determining the amount of sole material trimmed by said knives having a portion in advance, in the line of feed, of said randing knife extending into the rand crease between the sole 20 and upper, and means for engaging and feeding the sole being operated upon.

70. A machine for operating on the heel seats of boot and shoe soles, having in combination, a heel seat rough rounding knife, 25 a randing knife, means for feeding the sole comprising a movable tool constructed and operating to engage the sole for feeding by penetrating its face, and means for operating said tool to advance the sole and pre- 30 sent successive portions thereof to the action of said knives.

71. A machine for operating on the heel seats of boot and shoe soles, having in combination, two knives for operating on the

margin of the sole for rough rounding and 35 randing the heel seat, and means for engaging and feeding the sole being operated upon.

72. The combination with means for successively inserting fastenings into the heel 40 seat of a shoe fed past said means, of cutting means for rough rounding said heel seat and for producing a randing bevel at the edge of the rough rounding cut.

73. A machine of the class described, having in combination, mechanism for successively inserting fastenings into the heel seat of a shoe, a heel seat rough rounding cutter, a heel seat randing cutter, and means for moving said shoe and tools relatively to 50 transfer the point of operation of the tools around the heel seat.

74. A machine of the class described, having in combination, reciprocating work feeding means, a carriage movable to and fro 55 along the line of the work feed, connections between said work feeding means and carriage for moving the carriage, and an edge beveling cutter mounted upon said carriage and operating upon the return movement 60 thereof.

In testimony whereof I have signed my name to this specification in the presence of two subscribing witnesses.

WILLIAM H. BORDEN.

Correction in Letters Patent No. 1,145,055.

It is hereby certified that in Letters Patent No. 1,145,055, granted July 6, 1915, upon the application of William H. Borden, of Winchester, Massachusetts, for an improvement in "Machines for Use in the Manufacture of Boots and Shoes," an error appears in the printed specification requiring correction as follows: Page 8, line 124, claim 37, after the word "sole" insert the words *which shall extend*; and that the said Letters Patent should be read with this correction therein that the same may conform to the record of the case in the Patent Office.

Signed and sealed this 5th day of September, A. D., 1916.

[SEAL.]

F. W. H. CLAY,
Acting Commissioner of Patents.

Cl. 12—17:
